UNITED STATES PATENT OFFICE.

HAROLD EDGAR YARROW, OF SCOTSTOUN, GLASGOW, SCOTLAND.

SUPERHEATER FOR WATER-TUBE BOILERS.

1,143,476.

Specification of Letters Patent.

Patented June 15, 1915.

Application filed January 29, 1914. Serial No. 815,250.

To all whom it may concern:

Be it known that I, HAROLD EDGAR YARROW, a subject of the King of Great Britain, residing in Scotstoun, Glasgow, Scotland, and whose post-office address is care of Yarrow & Co. Limited, of Scotstoun, Glasgow, in the county of Renfrew, Scotland, have invented certain new and useful Improvements in Superheaters for Water-Tube Boilers, of which the following is a specification.

This invention relates to superheaters for water tube boilers and has for its primary objects to facilitate the re-tubing (partly or wholly) of the superheater, and the inspection, cleaning or stopping of the tubes.

The invention further comprises improvements in the baffling arrangements of single drum superheaters, whereby the steam is constrained to travel successively different sections of the superheater tubes, and also improvements in the means for distributing and controlling the flow of furnace gases among the tubes of such superheaters.

The invention will be hereinafter more specifically described with reference to the accompanying drawings, wherein—

Figure 1 is a part transverse section of a Yarrow boiler fitted with a superheater of the improved type; Fig. 2 is a longitudinal sectional elevation of the same; Fig. 3 is a longitudinal section on an enlarged scale of the superheater drum with parts broken away; Figs. 4 and 5 are transverse sections on lines 4—4 and 5—5 respectively of Fig. 3; Fig. 6 is a vertical section of the uptake for the furnace gases shown in Fig. 1 but on an enlarged scale; and Fig. 7 a part elevation of the damper controlling the uptake.

As shown in these drawings the superheater is of the single drum type with bent or U-shaped superheater tubes having both their ends expanded into the steam drum, and the invention applies in the main to superheaters of this type, although some of the improvements comprised in the invention are also applicable to other types of superheaters.

The steam drum *a* is formed of a single cylindrical tube of such diameter as will

enable the superheater tubes *b* to be expanded into the wall of the drum from the inside, and in the case of water tube boilers suitable for vessels of the destroyer class the drum would have a diameter of from 18 inches to two feet. The outside of the drum may be turned eccentric in relation to the inside so as to give an increased thickness of wall in that part of the drum into which the tubes *b* are expanded, and in order to increase the area of the space between the tubes at their lower ends as compared with the corresponding space at their upper ends the tubes are not arranged parallel with each other, viewed transversely, but are spread so as to increase their pitch in the transverse plane as they approach the drum (as indicated by the dotted lines in Fig. 1), thereby equalizing more or less completely (and without the use of baffles) the resistance to the flow of the furnace gases along all paths from the combustion space to the uptake. The tubes may, however, be spaced as usual without interfering with the other advantages of this invention.

Concentrically arranged within the drum *a* and extending throughout its whole length is a tube *c* which is supported by means of transverse partitions *d* which also divide the space between the tube and the drum into annular chambers, three such chambers being shown in the construction illustrated. Further, each of these chambers is divided into two parts *e*, *e'* by longitudinal partitions *c'* which, in conjunction with the transverse partitions *d*, cause the steam to follow the course hereinafter described.

The steam entering the inlet connection *f*, passes into the first section of the inner tube *c* and thence through slits *c'* to chamber *e*, whence it passes through the lower limbs of the superheater tubes *b* leading from this chamber, returning by the upper or outer limbs of the tubes to the chamber *e'*. From this chamber it passes through openings *d'* in the first transverse partition *d* to the chamber *e'* of the second section of the superheater drum, thence through the upper or outer limbs of the tubes belonging to this section, returning through the lower limbs of these tubes to the chamber *e*, and passing

thence through the slits c^o into the interior of the inner tube c , whence it passes direct to the third section of the superheater issuing from the inner tube of the same through the slits c^o in the wall of the tube which open into the chamber e , from which the steam passes to the lower limbs of the superheater tubes b belonging to this section, returning through the upper limbs to the chamber e' 10 and thence passing through the openings d^o in the end partition d to an end chamber g fitted with an outlet steam connection g' . This end chamber is closed by a cover g^o which can be removed to enable the inner tube c and the partitions d, e^o , which are secured by means of angle irons to the inner tube, to be withdrawn from the drum a and thereby permit access to the ends of the superheater tubes for the purpose of inspection or plugging.

It will be seen from the drawings, and in particular Fig. 2, that the first transverse partition d extends not only across the annular space between the drum a and the tube c , but also across the latter so as to cut off direct communication between the first and second sections of the tube c , while permitting communication through the opening d^o between the chamber e' and the first and second sections, whereas the second transverse partition d cuts off communication between the second and third sections of the drum but leaves the second and third sections of the tube c in direct communication with each other.

Should it be necessary at any time to re-tube the superheater either partly or completely, either or both of the steam connections f, g are removed and also if required the side casing h and the superheater drum and tubes are swung outwardly through a small angle about the axis of the drum to a position such as indicated by the line x, y in Fig. 1, which permits the operations of removing and replacing one or more tubes to be carried out.

The uptake through which the gases pass after traversing the outside of the superheater tubes may be controlled by a hinged damper i preferably balanced by a counter-weight indicated in dotted lines at j , Fig. 1. This damper is preferably made in sections (three are indicated in the drawings) and each section is pivotally connected at or near its center with an arm k fast on a spindle m which is preferably hollow for the introduction of a cooling medium and extends longitudinally of the boiler along the whole length of the uptake, suitable means being provided to work the damper from the stokehole without the use of long rods and gearing. The spindle m is supported at suitable intervals in bearings carried by brackets n fixed to a wall of the uptake, and

stops o , of which there are preferably two 65 in each section of the damper, are secured at appropriate points on the opposite wall of the uptake to arrest and support the outer edge of the damper when in the closed position, the inner edge (which is preferably 70 slightly curved for the purpose) passing between the lower side of the spindle m and a longitudinal plate or baffle p , so as to occupy the position shown in dotted lines in Fig. 6.

Having thus described the nature of the 75 said invention and the best means I know of carrying the same into practical effect, I claim:

1. A superheater for water tube boilers having a single steam drum, wherein the 80 drum is fitted with an inner tube and transverse and longitudinal baffles dividing the drum into sections, substantially as described.

2. A steam superheater having a single 85 steam drum and an inner tube and transverse and longitudinal baffles dividing the drum into sections, said inner tube and baffles being removable upon removing an end or cover plate, substantially as described. 90

3. A steam superheater having a single steam drum and an inner tube and transverse and longitudinal baffles dividing the drum into sections, said inner tube and baffle being removable in one piece upon removing 95 an end or cover plate, substantially as described.

4. A superheater for water tube boilers of the kind in which superheater tubes, of substantially U-shape are expanded into a single steam drum with the tubes projecting upwardly, wherein the drum is adapted to be rotated about its longitudinal axis either with or without removal of the side casing of the furnace so as to project the tubes forward or outward to render them accessible for the purpose of removal or replacement, substantially as described.

5. A steam superheater having a plurality of bent or U-shaped elements expanded into 110 a single steam drum or header, the legs of adjacent elements being throughout their whole length out of parallel so that the gas passage space between them increases in the direction toward the drum or header. 111

6. The combination with a steam superheater comprising a plurality of bent or U-shaped tubes expanded into a single steam drum, of means for controlling the flow of the heating gases, comprising a damper 112 made in one or more sections each pivotally hung at or about its center upon an arm or arms carried by a rotatable spindle, substantially as described.

7. In a superheater for water tube boilers, 113 the combination with a single steam drum or header of an inner tube and baffles dividing said drum into sections, a plurality of

bent or U-shaped superheater elements expanded into said drum, the legs of adjacent elements being arranged out of parallel with one another, and means for rotating said drum and superheating elements about the axis of the drum, substantially as hereinbefore described.

In testimony whereof I have signed my name to this specification in the presence of two subscribing witnesses.

HAROLD EDGAR YARROW.
